FURNITURE STABILIZING DEVICE

Frank W. Ingram, Erdington, Birmingham, England

Application July 7, 1954, Serial No. 441,879

Claims priority, application Great Britain July 16, 1953

3 Claims. (Cl. 45—139)

My invention relates to stabilizing devices with particular reference to items of furniture which are unstable due to irregularities in the length of the legs or feet of such furniture or to standing upon an uneven surface.

The increasing use of light tubular steel and wooden furniture, particularly in licensed premises and restaurants, emphasizes the advantage of such furniture that it may be slid away to permit cleaning of the floor upon which it normally stands or that it may be removed to allow the floor space to be used for some other purpose, e. g. dancing or cabaret.

Unfortunately, however, due to constantly changing the position of such furniture, irregularities in the level of the floor and the length of the legs of the furniture, it is often the case when such furniture is returned to a position on the floor it is found to be standing on three legs only and as a result is unstable.

The instability can be the cause of intense irritation to customers and patrons, and is frequently the cause of considerable damage to clothing by virtue of the upsetting of liquid containers standing upon the furniture, by waiters, persons or animals brushing against the items of furniture.

In order to eliminate the instability, it is necessary to supply means to close the gap between the offending leg or foot and the surface upon which it stands.

It is also necessary that such means shall automatically adjust themselves to differences in the size of the gap corresponding to different positions of the furniture relative to the surface upon which it stands, and also to offer a substantially solid resistance to such movement of the furniture as is likely to cause the accidental upsetting of containers previously referred to.

It is an object of the present invention to supply such means and it is a further object of the invention to supply an article of furniture having a leg or legs which incorporate distensible means for automatically filling any gap which may exist between one of such legs when the furniture is stood upon a floor or like base upon the other legs of the furniture.

According to the present invention, a device for stabilizing an article of furniture comprises a plug or the like secured to and movable relative to a member and resilient means urging said plug away from said member wherein said plug is moved toward said member at a controlled speed and said resilient means are collapsed when a minor proportion of the weight of said article of furniture is borne by the device.

The member may be the item of furniture but preferably the plug is slidable in a housing which is adapted to be secured within a recess formed in a leg or like support of the article of furniture so that it is immovable relative thereto.

Preferably also the resilient means is a spring but a resilient metallic bellows member, being in itself a spring, may also be used.

The function of the resilient means, however, is limited to that of extending the device when a condition of "No-

2

Load" is applied. It is not a function of the resilient means to support the table in any way and these means should be sufficiently light to collapse under a load of e. g. 12 ounces.

5 The means for controlling the speed of movement of the plug may comprise a piston and cylinder mechanism whereby hydraulic fluid in the cylinder is permitted to leak slowly past the piston or, alternatively, it may comprise a friction member engaging a rod with a predetermined degree of frictional resistance.

10 It is preferable also that control of the speed of movement of the plug relative to the member be exercised mainly when the plug is moving toward the member in order that the resilient means may be free to extend the plug from the member in the shortest possible time.

15 In a preferred embodiment a tubular housing is closed at one end and a hollow plug also closed at one end is slidable within the open end of said housing. A helical spring is enclosed within the housing having one end 20 abutting the closed end thereof, and the other end abutting the adjacent end of the plug. The means for controlling the speed of movement of the plug comprises a piston slidable within the plug which projects from the housing and which is partially filled with hydraulic fluid. The 25 piston is connected by means of a rod to the closed end of the housing and is adapted for limited movement relative to said rod between two axially spaced locating washers. A bush is secured to the open end of the plug having a concentric bore in which the piston rod is slidably supported, and a plurality of grooves is formed on that face of the piston remote from said housing.

20 In a further embodiment of the invention, the plug is solid, and the housing is tubular and divided into an upper and a lower chamber by a partition fluid tightly secured within the bore thereof. A distensible bellows member having a helical spring associated therewith, or being in itself resilient, is enclosed within the lower chamber, one 30 end thereof being fluid tightly secured to the said partition and the other end abutting that end of the plug permanently enclosed within the housing. A metering hole formed in said partition and in that end of the distensible member fluid tightly secured thereto connects the interior of said distensible member with the upper chamber formed by the partition within the housing whereby fluid may 35 pass from said distensible member to the upper chamber when the distensible member is longitudinally contracted. A rod secured to the partition and extending into the interior of the distensible member limits the movement of said distensible member upon contraction, and a ball valve 40 within the metering hole permits a more rapid flow of fluid for one direction of movement of the plug than for the other.

45 In yet a further embodiment of the invention, the plug is hollow but closed at one end and has a bush secured within the open end thereof, said bush having a co-axially aligned taper bore, the larger diameter end of which lies remote from the closed end of the plug. A rod extending from the closed end of the housing is adapted to pass coaxially through said taper bore, and a flange formed 50 on that end of the rod remote from the closed end of the housing is adapted to engage one end of said bush to prevent the rod from leaving the bush. A plurality of segmental shaped wedges of friction material are located round the rod within the taper bore, whereby the rod is gripped by the wedge action of the said wedges when moved in one direction, but extracts the wedges from the taper bore when moved in the other direction. A light 55 helical spring having one end abutting the closed end of the housing retains the wedges within the taper bore and a further helical spring of larger diameter, abuts the closed end of the housing at one end and the plug at the other end.

In order that the invention may be more fully described, reference is made to the accompanying drawings of which:

Figure 1 is a section of a stabilizing device constructed according to the invention.

Figure 2 is an end view of a piston to be incorporated in the embodiment shown in Fig. 1.

Figure 3 is a sectional view of an alternative embodiment of the invention.

Figure 4 is a sectional view of a further embodiment of the invention.

Figure 5 is a part sectional view of a table leg having a stabilizing device constructed according to the invention, secured thereto.

Figure 6 is a sectional view of alternate means of securing a stabilizing device of the present invention to a leg or support of a tubular steel item of furniture.

In one embodiment of the invention (Figs. 1 and 2) a cylindrical plug 1, closed at one end is slidable within a cylindrical housing 2, which is also closed at one end. A cylindrical bush 3 is secured within the open end of the plug 1, the bore of which is coaxially aligned with the bore of the cylindrical plug 1. A piston rod 4 extends through said bush 3 and is secured to the end wall of the housing 2 by means of a nut 6 which engages with a threaded portion of the piston rod 4, and an annular piston 5 (Fig. 2) having an internal diameter larger than the diameter of said piston rod 4 is located thereon between locating washers 7 and 8. A plurality of grooves 9 are formed in that face of the piston adjacent the closed end of the plug 1 and sufficient hydraulic fluid is contained in the plug to fill it completely when the locating washer 7 abuts the closed end thereof. A helical spring 10 is enclosed within the housing 2, one end of which abuts the end wall of said housing 2 and the other end abuts the adjacent end of the plug 1. A sealing ring 11 is located in a groove 11a formed in the bush 3 to prevent the escape of hydraulic fluid from the plug.

The device operates as follows. When the plug 1 is moved inwardly of the housing 2 against the action of the helical spring 10, the force moving the plug 1, hereafter described as the compressing force, is resisted by the reaction of the piston 5 against the hydraulic fluid, the piston 5 being forced against the washer 8 to prevent the flow of hydraulic fluid past the inner periphery of the piston, but if the compressing force is maintained, hydraulic fluid flows past the piston 5, between the outer periphery thereof and the walls of the plug 1 at a rate dependent upon the clearance between said outer periphery and said walls for a given compressing force, whereby the device is eventually contracted to the point where the locating washer 7 abuts the closed end of the plug 1. When the compressing force is removed, the helical spring 10 moves the plug 1 outwardly of the housing 2 and the washer 7 thus moves to abut the piston 5. This movement provides a free passage for the hydraulic fluid, past the inner periphery of the piston 5 and along the grooves 9 formed in the face thereof thus permitting rapid expansion of the device to the point wherein the locating washer 8 abuts the bush 3 to prevent further expansion.

One such device is fitted into the end of each leg 32 (Fig. 5) for support of an item of furniture e. g. a table having four legs, so that when the table stands upon its legs on an irregular floor or like surface the closed end of the plug 1 abuts the floor and the device is at substantially right angles to the said floor. At least three of the legs thereof will be in contact with the floor and the device of the fourth leg will be suspended some distance above the floor, and fully extended by the action of the helical spring 10. Due to the weight of the table, pressure will bear on those three devices contacting the floor which will cause them to be contracted in the manner previously described. The contraction will continue until the gap between the device of the fourth leg is taken up and this device will then contract with the other three until these

three are fully contracted and wholly contained within the leg or support of the item of furniture.

With the table in this position, any sudden pressure brought to bear on any of the legs of the table will be thus solidly resisted, either by the reaction of the piston of the device on the hydraulic fluid or by the end of the leg on the floor if the particular device secured to that leg is fully contracted.

Sustained pressure, however, if directed to a device 10 which is not fully contracted, hereinafter described as the device under consideration, will cause it to be further contracted in the manner previously described, the speed of such contraction being controlled by the clearance between the outer periphery of the piston of the device 15 and the walls of the plug, the table meanwhile pivoting upon those two legs adjacent to and at substantially right angles to the leg holding the device under consideration. The device of the remaining leg i. e. the leg diametrically opposite, will, however, extend under the action of its 20 helical spring in direct proportion to the amount of contraction of said device under consideration, so that at all times all four devices are in contact with the floor or like surface upon which the table stands.

9785 9790 9795 9800 9805 9810 9815 9820 9825 9830 9835 9840 9845 9850 9855 9860 9865 9870 9875 9880 9885 9890 9895 9900 9905 9910 9915

return valve into the chamber 18 and the bellows member contracts longitudinally until the end which lies adjacent the plug 12 abuts the end of the stem 20 and restricts further movement of the plug in this direction.

When the compressing force is removed, the helical spring 23 moves the plug outwardly of the housing, the quick return valve permitting a rapid flow of fluid in this direction from chamber 18 to chamber 17 whereby the device extends rapidly to the point where the taper portion 13 of the plug 12 abuts the taper portion 15 of the housing to restrict further movement of the plug in this direction.

While this embodiment has described a distensible bellows member co-operating with a helical spring 23, it should be understood that the bellows member may be metallic, and in itself sufficiently resilient to eliminate the necessity for such a spring.

One such device is fitted into the end of each leg or support of an item of furniture in the manner described in the previous embodiment and functions in a similar manner to stabilize the item of furniture.

In yet a further embodiment of the invention (Fig. 4) a cylindrical plug 24 closed at one end is slidable within a cylindrical housing 25 which is also closed at one end. A cylindrical bush 26 is secured within the open end of the plug 24, the bore of said bush being tapered and coaxially aligned with the bore of the cylindrical plug 24 and has the larger diameter thereof at that end of the bush 26 remote from the plug 24. A rod 27 extends coaxially through the taper bore of the bush 26 having one end secured to the end wall of the housing 25 and the other terminating in a radially extending flange 28 of larger diameter than the smaller diameter of the taper bore of the bush 26.

A plurality of substantially wedge shaped members 29 of segmental cross section and being formed of friction material are enclosed within the space between the taper bore of the bush 26 and the adjacent periphery of the rod, being retained therein by a helical spring 30 one end of which abuts the end wall of the housing 25 and the other end of which abuts the adjacent ends of the wedge shaped members 29. A further helical spring 31 is located within the housing 25, one end abutting the end wall thereof and the other end abutting the adjacent end of the plug 24.

The device operates as follows. When the plug 24 is moved inwardly of the housing 25 against the action of the helical springs 30 and 31, the compressing force is resisted by the frictional resistance between the wedge shaped members 29 and the rod 27, such force being increased by the tendency of the rod 27 to force the wedge shaped members 29 further into the taper bore of the bush 26. When a predetermined compressing force is exceeded, however, the wedge shaped members 29 slide along the rod 27 and permit the plug 24 to move inwardly of the housing 25, such movement being restrained by the frictional resistance. This movement may continue until the helical spring 31 is fully compressed and forms a solid tube between the end wall and the housing 25 and the end of the plug 24.

When the compressing force is removed the helical spring 31 moves the plug 24 outwardly of the housing 25 whereby the wedge shaped members are drawn outwardly of the taper bore of the bush 26 thereby reducing the value of the frictional resistance between said members 29 and the rod 27, thus permitting rapid expansion of the device to a point whereby the flange 28 abuts the adjacent end of the bush 26, to prevent further movement of the plug 24 relative to the housing 25.

10 The device is fitted to an item of furniture and functions to produce the stabilizing effect as described in the previous embodiments.

15 While the invention has been described showing one device secured to each leg or support of an item of furniture, it should be understood that this is not essential. In the case of e. g. a wardrobe which is not likely to be moved from one position upon a floor, the use of a single device secured to a single leg or like support could adequately deal with an irregularity in the floor level at that 20 particular position.

25 Furthermore, casters or other known devices to permit ease of movement of such items of furniture may be secured to the movable plug portion of my stabilizing device, or be formed as an integral part thereof, and similar stabilizing devices having means to increase the area of contact between an item of furniture and the floor or support on which it stands are considered to be within the scope of my invention.

Having now described my invention, what I claim is:

30 1. A furniture stabilizing device which comprises a housing open at its lower end, a hollow plug slidable vertically in said housing and closed at its upper end, a rod secured to the upper part of said housing and extending co-axially substantially fluid tightly and slidably through the closed upper end of said plug into said plug, said rod having a pair of spaced surfaces within said plug to form an annular recess, a spring pressing said plug downwardly to project from the lower end of the housing and a floating annular disc in said recess and having a slight clearance with the inner peripheral surface of said plug to form a restricted passage therewith, said disc being movable to a fluid-tight contact with the upper surface of said recess and movable to a fluid-free contact with the lower surface of said recess, said recess and disc providing passages for the fluid when in contact.

40 2. The furniture stabilizing device of claim 1 in which the lower surface of said floating annular disc is grooved to provide fluid passages when said disc is in contact with the lower surface of said recess.

45 3. The furniture stabilizing device of claim 1 in which said hollow plug contains a liquid.
